US0D1084935S

(12) **United States Design Patent** (10) **Patent No.:** **US D1,084,935 S**
(45) **Date of Patent:** **** Jul. 22, 2025**

(54) **REAR BUMPER**

(71) Applicant: **VOLVO CAR CORPORATION**,
Gothenburg (SE)

(72) Inventor: **Katharina Sachs**, Gothenburg (SE)

(73) Assignee: **VOLVO CAR CORPORATION**,
Gothenburg (SE)

(**) Term: **15 Years**

(21) Appl. No.: **29/892,775**

(22) Filed: **May 22, 2023**

(30) **Foreign Application Priority Data**

Nov. 25, 2022 (EM) 015004285-0005

(51) **LOC (15) Cl.** **12-16**

(52) **U.S. Cl.**

USPC **D12/169**

(58) **Field of Classification Search**

USPC D12/1, 14, 22, 82, 85-93, 96-99,
D12/163-167, 169-173, 181, 184-185,
D12/190, 196, 400; D21/434, 533, 548,
D21/552, 561

CPC B60R 19/54; B60R 19/02; B60R 19/18;
B60R 19/24; B60R 19/56; B60R 19/04;
B60R 2019/1886; B62D 25/08; B60D
35/005; B60T 5/00

(57) **CLAIM**

The ornamental design for a rear bumper as shown and described.

DESCRIPTION

FIG. 1 is a front perspective view thereof;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is a rear perspective view thereof.

1 Claim, 8 Drawing Sheets
